UNITED STATES PATENT OFFICE.

CYRUS F. WICKER, OF WASHINGTON, DISTRICT OF COLUMBIA.

STAFF-GUN AND PROJECTILE.

1,195,543.

Specification of Letters Patent. Patented Aug. 22, 1916.

Application filed September 2, 1915. Serial No. 48,657.

To all whom it may concern:

Be it known that I, CYRUS FRENCH WICKER, a citizen of the United States, and a resident of Washington, District of Columbia, have invented a new and useful Improvement in Staff-Guns and Projectiles, of which the following is a specification.

With modern methods of trench warfare and their consequent use of hand grenades, shrapnel or bombs that are thrown only short distances, in most cases by hand, the necessity for a compact portable device for relieving the soldiers of this tiresome task has arisen and the present invention is the result thereof.

The object of the invention is to first devise a gun for projecting the projectiles that is so light that each soldier may be equipped with one of them, and second, to produce a projectile for the gun that will be of maximum size and yet of minimum weight so that no difficulty will be experienced in the handling of them either by the operator of the gun or in dealing them out to the operators.

With this and other objects in view, the invention consists in the combination, arrangement and construction of parts hereinafter described and particularly pointed out in the claims it being understood that I do not intend to limit myself to the details of construction of the various parts.

The invention is illustrated in the accompanying drawing in which—

Figure 1 is a perspective view partly in section showing my staff gun in firing position. Fig. 2 shows a side elevation of one form of projectile showing in particular a grooved flange. Fig. 3 is similar to Fig. 2 except it shows the way the flange of the projectile of Fig. 2 will look after firing. Fig. 4 shows another form of projectile having depending fingers in place of flanges. Fig. 5 is a sectional view of the device of Fig. 4 taken along the lines 5—5 and is to show a possible form of the fingers. Fig. 6 shows a modified form of staff gun as does Fig. 7.

In the drawing the numeral 10 indicates the staff or gun of my device. It is pointed at one end, which end is adapted to penetrate the ground 11 and a pivoted collar 12 having a sharp flange is provided on the staff which will resist recoil of the explosions. At the upper end, the staff is hollow so that a firing element 13 may be placed therein

which will have a trigger mechanism 14 and a spring 15 coacting therewith. My improved projectile is indicated at 16 upon the staff and consists of a main portion of spherical or other shape having depending solid flange 17 adapted to encircle the upper end of the staff when in firing position. The flange 17 forms a recess 18 in which is placed, between the projectile and the end of the staff, a disk of high explosive 19.

As a modified form of the projectile, it may be equipped with flange 20 made of some ductile but tough material which may be provided with grooves 21 or equivalent devices forming lines of least resistance.

22 indicates the form the flange 20 takes after the explosion takes place.

As another form of projectile, the flanges may be modified into depending fingers 23 which may be of ductile material similar to the flange 20 or they may be of some rigid material and made in triangular shape in cross section.

The gun 10 of Fig. 1 may be modified from an explosive gun to a spring gun as shown in Fig. 6 in which 10 is a staff provided with a hollow interior in which may be located a very strong spring 24 with a compressing mechanism 25 and a trigger mechanism 26.

In operation, the staff is driven into the ground at the angle ordered upon which, of course, the range depends. The driving continues until the engagement of the collar 12 with the ground prevents any further driving, the collar being pivoted will adapt itself to any angle that the staff may be to the ground. The firing element is then locked in withdrawn position and the projectile is fitted over the end of the staff as shown in Fig. 1, the explosive disk first being placed on the end of the staff. Then when it is desired to fire the projectile, it is only necessary to release the trigger mechanism whereupon the firing element is forced upwardly by means of the spring pressure so that it sets off the explosive disk. However, under certain circumstances it may be necessary to have the disk made of some high explosive, such as, fulminate and in such a case, the solid flanges would be shattered to such an extent that the operator of the gun would be liable to injury. In order to overcome this shattering, the flanges of Figs. 2 and 3 have been devised of some tough ductile material

so that when the explosion takes place in-

stead of shattering, it simply splits the flanges along the lines of least resistance, which may or may not be previously made grooves 21, so that the flanges are bent outwardly as shown in Fig. 3, with no harm resulting to the operator. In cases where the explosive would be not quite so violent as fulminate but yet too violent to be withstood by the solid flanges, fingers 23 may be provided on the projectile. These may either be of ductile material to bend as the flanges in Fig. 3 or they may be made rigid. In the event of their being rigid they would be made triangular in cross section as shown in Fig. 5 with the apices of the triangle pointed inwardly. This leaves room for the explosion to escape as shown by the arrows through the spaces 24 between the triangular fingers 23 without harming the fingers.

It will thus be seen that the flanges serve in the various capacities of seating means, explosion resisting means and guiding means. I do not intend to limit myself to any one of these functions as I may use each or any combination of them.

I consider the flanges and the fingers the equivalent of each other so that where one is mentioned, it is to be understood that I may substitute the other in its place. This is especially true when it is considered that the flanges result in fingers after the explosion and that if fingers are used they must be made slightly ductile or else they will be blown off by the explosion.

Under certain circumstances it may not be

desirable to use an explosive gun as shown in Fig. 1, in which case, I may use a spring gun as shown in Fig. 6 which would have the advantage of being much lighter and therefore more portable. This would be because its dimensions would not have to be so great as no explosion has to be withstood and also the projectile could be made lighter because it similarly would not have to withstand the greater pressure of an explosion. The gun in Fig. 6 is provided with a very strong spring located in a hollowed out portion which may be compressed by any pressing mechanism 25 and then may be released by any trigger mechanism 26 whereby the projectile may be projected in all other respects similar to the gun in Fig. 1. Again, instead of providing the flanges or fingers upon the projectile, they may be provided upon the gun 10 as at 27 in Fig. 7 so that the projectile 16' may fit therebetween and be retained upon the gun until projected therefrom.

What I claim is:

1. A projectile having a combined explosion and gun receiving cavity formed by a depending flange deformable by the explosion.

2. A projectile having a combined explosion and gun receiving cavity formed by a depending flange of tough ductile material and weakening grooves on said flange.

3. A projectile having a rigid body portion, and a combined explosion and gun receiving cavity bounded by ductile walls.

CYRUS F. WICKER.
